APPLE PACKING DEVICE

Charles L. Taylor, Biglerville, Pa.

Application May 14, 1935, Serial No. 21,456

1 Claim. (Cl. 226—17)

This invention relates to an apple packing device.

In a more specific aspect, the invention contemplates the provision of a novel facing plate or pan and cooperating form for use in packing apples in crates.

It has heretofore been proposed to pack apples in baskets and the like by first preparing a finished layer of the fruit that is intended to face the packed container. In this method a facing plate is employed together with a packing form.

Usually the method embraces, first, preparing a facing layer of apples on a so-called facing plate; second, placing a form on the plate over the facing layer; third, filling the form in which has been pre-positioned a self-sustaining liner; fourth, removing the form; fifth, placing the basket to be packed over the liner containing an adequate charge of apples; and, sixth, inverting the basket containing the fruit together with the facing plate, removing the latter, and exposing the finished layer of fruit at the top of the basket.

Various complicated tables and expedients have been developed for use in this method of packing which render the same cumbersome and expensive.

It is the specific purpose of the present invention to provide a novel device of great simplicity especially designed for packing rectangular crates of a character invented by me and disclosed and claimed in my copending application Serial No. 21,457, filed concurrently herewith.

It is a further object of the invention to provide a light-weight, sheet metal, cooperative packing form and base or facing plate that can be produced at a minimum cost and that will be efficient in use. It is more particularly an object of the invention to provide such a form of light weight and yet so construct and reinforce it that it will withstand the strains to which it is subjected in use.

Further and more detailed advantages of the invention will appear as the description thereof proceeds.

In the accompanying drawing, in which like reference numerals indicate like parts:

Figure 1 represents a plan view showing the charge retaining form in position on the facing plate or pan;

Figure 2 is a sectional view along the line 2—2 of Figure 1; and

Figure 3 is a plan view of the base or facing plate without the retaining form.

Referring to the drawing, reference character

1 indicates generally the facing plate or pan, and reference character 2 indicates generally the charge retaining form. The facing plate or pan 1 embraces a substantially rectangular sheet metal plate 3 of sufficient area to provide an adequate flange 4, extending outwardly, completely around the base 5 of the sustaining form 2 when the latter is in position on the facing plate 1.

To give rigidity and strength to the plate 3 and to further function in the manner to be described hereinafter, there are provided substantially rectangular walls 6 and 7 affixed to the sheet metal plate 3 of the facing plate or pan 1. The wall 6 projects below the plate 3 and constitutes a support for the pan 1. The wall 6 is provided with a flange 8 by which it is secured to the plate 3. The wall 6 further extends from the plate 3 a distance adequate to permit, when the facing plate or pan 1 is resting on a support, the free passage of the fingers of an operator beneath the flange 4 to permit lifting of the plate 1 together with the sustaining form 2. It will be additionally observed that the wall 6 is positioned interiorly of the wall 7. This is done to bring the sustaining wall into a more central position with respect to the sheet metal plate 3 upon which the charge of fruit is supported.

The vertical wall 7 extends upwardly from the plate 3 a distance substantially equal to that of the thickness of a layer of apples. The function of the wall 7 is at least three-fold. First, it acts to define the area on the facing plate 1 that is to be covered by the facing layer. Second, it telescopically holds the sustaining form 2 in a secure position upon the facing plate 1 during the time that the charge of apples is being poured or placed into the sustaining form. Third, it adds rigidity and reinforcement to the sheet metal plate 3 of the facing plate 1. Additionally, because of the position of the vertical wall 7 intermediate the circumferential edge of the facing plate 1 and the lower wall 6, the flange 4 is strengthened so that it will not buckle in lifting the facing plate together with the charge. It will also be observed that this rigidity prevails throughout the circumference of the facing plate. Furthermore, the wall 7 terminates at its base in an outwardly extending flange 9 that projects to the edge of the facing plate 1, the plate 3 of which is rolled over the extremity of the flange 9 as indicated at 10. This further adds rigidity and strength to the

facing plate and gives the same a neat peripheral finish.

Coming next to a detailed description of the sustaining form 2, it will be observed that the 5 larger end of this form, indicated at 5, just freely telescopes over the upwardly extending wall 7 of the facing plate 1. The sustaining form 2 is greatly strengthened by virtue of the particular configuration of the corner structure 10 which is indicated at 11. It will be observed that this corner structure acts to brace the side walls 12 and the end walls 13 of the sustaining form 2. Additionally, it will be observed that, in order to further reinforce the longer side 15 walls 12, the metal is joined along vertical lines substantially centrally of the ends of these walls as shown at 14. The walls 12, being of the greatest extent, are more likely to buckle when a charge is suddenly poured into the sustaining 20 form 2. It is for this reason that the side walls 12 are thus reinforced by the double-thickness metal joint shown at 14. To provide smooth peripheral edges on the sustaining form 2, the marginal edges thereof are rolled, as indicated at 25 15 and 16, and to further strengthen the sustaining form, there is positioned in the rolls 15 and 16 a reinforcing wire 17.

In the use of the improved packing device, the 30 facing plate or pan 1 is positioned on a table and has the appearance shown in Figure 3. The operator then prepares a facing layer of apples in this plate; the sustaining form 2 is next telescoped down over the wall 7 in the manner shown in Figure 2; a self-sustaining paper liner 35 (not shown) is inserted in the sustaining form 2; and the charge of apples is next poured into the sustaining form. The form 2 is then re-

10 moved, and a crate having a configuration substantially conforming to that of the form 2 is passed down over the self-sustaining liner containing the preformed charge of apples, whereupon the operator grasps the plate 1 under the 5 flange 4 and turns the container, together with the charge of fruit and the facing plate 1, over into proper position, after which the facing plate is removed and the finished layer of apples at the top of the container exposed.

15 From the foregoing description it will be apparent that I have provided a novel fruit packing device possessing the advantageous characteristics hereinbefore pointed out.

Having thus described my invention, what I 15 claim is:

In an apparatus for packing fruit, a facing 20 plate comprising a flat sheet metal member, an upstanding octagonal member carried by said flat sheet metal member, said upstanding member having a lower marginal flange projecting therefrom and secured to said flat sheet metal member, the marginal edges of said flat sheet metal member being rolled around the marginal edge of said flange to form a smooth gripping 25 finished bead extending substantially entirely around the marginal edge of said facing plate, a rectangular supporting wall secured to the lower side of said flat sheet metal member through the medium of a second horizontally extending 30 flange, said last-mentioned flange terminating in substantial alinement with the inner surface of said upstanding member whereby the base of said upstanding member is rigidly supported on said flat sheet metal member.
